US00D951268S

(12) **United States Design Patent** (10) **Patent No.:** **US D951,268 S**
Dye et al. (45) **Date of Patent:** **** May 10, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Alan C. Dye**, San Francisco, CA (US);
Jonathan P. Ive, San Francisco, CA (US); **Christopher Wilson**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/721,173**

(22) Filed: **Jan. 17, 2020**

Related U.S. Application Data

(63) Continuation of application No. 29/633,258, filed on Jan. 12, 2018, now Pat. No. Des. 873,279, which is a continuation of application No. 29/578,141, filed on Sep. 19, 2016, now Pat. No. Des. 807,905, which is a continuation of application No. 29/565,613, filed on May 23, 2016, now Pat. No. Des. 797,135, which is a continuation of application No. 29/501,182, filed on Sep. 2, 2014, now Pat. No. Des. 757,079.

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof and form no part of the claimed design.

1 Claim, 1 Drawing Sheet
